[57] CLAIM

The ornamental design for a freestanding moistened towelette dispenser and waste disposal device, as shown and described.

DESCRIPTION

FIG. 1 is a perspective view of a freestanding moistened towelette dispenser and waste disposal device of our new design, with a towelette shown in broken line, in the dispensing position, for illustrative purposes only; FIG. 2 is a top plan view of our new design as shown in FIG. 1;

FIG. 3 is a bottom plan view of our new design as shown in FIG. 1;

FIG. 4 is a front plan view of our new design as shown in FIG. 1;

FIG. 5 is rear plan view of our new design as shown in FIG. 1;

FIG. 6 is left side plan view of our new design as shown in FIG. 1, with the opposite, or right side view being the mirror image thereof; and,

FIG. 7 is a perspective view of our new design, similar to FIG. 1, with the lid of the towel dispensing portion thereof in the open or raised position to show, in broken line, a roll of moistened towelettes mounted therein, for illustrative purposes only, and the lower, waste disposal portion thereof in the open, or slid out position.
